CHILD'S BED

Roman B. Bukolt, Stevens Point, Wis.

Application June 27, 1940, Serial No. 342,808

2 Claims. (Cl. 5—11)

The invention relates primarily to a child's bed of the general type having a mattress-carrying spring frame vertically adjustable to different elevations, and in the present disclosure, said frame is adjustable to a relatively high position convenient for dressing a child; to a relatively low or normal position; to an intermediate position about even with the mother's bed for convenience at night; and to an inclined position often beneficial if the child be ill.

The object of the invention is the provision of a generally improved and simplified construction which provides for quick and easy adjustment of the mattress-carrying frame to, and support of, said frame in any selected position.

With the foregoing in view, the invention resides in the novel subject matter hereinafter described and claimed, description being accomplished by reference to the accompanying drawings.

Figure 1 is a side elevation showing the mattress-carrying frame supported in an inclined position.

Figures 2, 3 and 4 are enlarged side elevations, partly in section, showing one end of the mattress-carrying frame in fully raised, intermediate and fully lowered positions, respectively.

Figure 5 is a horizontal section on line 5—5 of Fig. 3.

Figure 6 is a perspective view of one end of the mattress-carrying frame.

Figure 7 is a perspective view of one of the vertically swingable supports for said end of the mattress-carrying frame.

A preferred construction has been illustrated and will be rather specifically described, with the understanding, however, that within the scope of the invention as claimed, variations may be made.

The bed herein shown is of the crib type in which a head 10 and a foot 10^a are connected and held in fixed relation with each other by crib sides 11, one or both of which may be mounted for vertical adjustment, for instance, along tracks 12, 12^a. A mattress-carrying spring frame 13 extends from the head 10 to the foot 10^a and novel provision is made for holding said frame 13 in positions to which it may be vertically adjusted, and as said provision is the same at both the head and the foot of the bed, only that at the head will be described, and all reference numbers used in the description will be found on the corresponding parts at the foot of the bed, associated with the suffix (a).

Two vertically swingable arms 14 are pivoted

to the head 10 as indicated at 15, the pivotal axes being alined with each other and disposed transversely of the bed. These arms are connected with each other by a horizontal rod 16 which is parallel with the axes of the connections 15 and spaced from said axes, said rod being somewhat longer than the width of the frame 13, in the present disclosure. The arms 14 may be considered as having inwardly projecting rigid portions at their free ends, formed in the present disclosure by the end portions of the rod 16. The adjacent end of the frame 13 is provided with downwardly open notches 17 which receive the end portions of the rod 16 when said frame 13 is fully raised as in Fig. 2 or fully lowered as in Fig. 4. The frame 13 is customarily provided with side and end bars of angle metal, and the vertical flanges of the side bars may be cut short and inwardly spaced from the corresponding flange of the end bar to provide the notches 17.

In inwardly spaced relation with its notched end, the frame 13 is provided with other notches 18 which open toward said end and receive the end portions of the rod 16 when said frame is in the intermediate position shown in Fig. 3, said frame having lateral lugs 19 which then rest on the arms 14, these lugs 19 being idle when frame 13 is either fully raised or fully lowered. The notches 18 are preferably formed in lugs or hooks 20 which are secured to and project downwardly from the side bars of the frame 13 and it is preferable that each notch have a depression 21 in its lower edge wall to snugly receive the rod 16, assisting in securely holding the frame 13 against endwise movement. It is also preferable that the arms 14 be so constructed that when the rod 16 is in the notches 17 with said frame either raised or lowered, portions of said arms will lie solidly against the head 10 to prevent endwise movement of said frame 13.

In the preferred form of construction, the arms 14, the rod 16 and parts of the pivotal connections 15 are formed from a single length of metal rod, the extremities of this rod being bent laterally outward to provide trunnions 22 which are received in suitable bearings 23 secured to the head 10, said trunnions and bearings constituting said pivotal connections 15. At their juncture with the rod 16, the arms are preferably given a return bend 24, providing stops to abut the outer longitudinal edges of the frame 13, preventing movement of said frame transversely of the bed. When the frame 13 is fully raised, the bends 24 extend upwardly and inwardly from the arms 14 and the latter lie solidly against the head 10. When the

frame 13 is fully lowered, the bends 24 extend downwardly and outwardly from the arms 14 and abut the head of the bed. When the frame 13 is in its intermediate position, the bends 24 are disposed at the outer sides of the lugs 20 and the frame then lies between the arms 14, said frame being thus held against movement transversely of the bed.

It is preferable to provide a lifting handle 25 on the end of the spring 13 to facilitate lifting when the mattress is in place, and each time the frame is to be adjusted to another position, it is necessary to first lift it until the rod 16 is free of the notches 17 or 18, to then swing the arms 14 and the rod toward the new position which they are to occupy, and to finally re-engage the rod with the notches 17, or engage it with the notches 18, as required. It will be observed that the same notches 17 receive the rod 16 when the frame 13 is either fully raised as in Fig. 2 or fully lowered as seen in Fig. 4. With the frame lifted by means of the handle 25, the arms 14 and rod 16 may be either swung to fully upstanding position or to fully hanging position before engagement of the notches 17 with said rod. Whenever the frame 13 is to be supported in the intermediate position of Fig. 3, it is of course first necessary that it be raised sufficiently to permit entrance of the rod 16 into the notches 18, and such entrance of rod into notches will occur when the frame is then properly lowered, the relative movement of frame and arms which occurs during this lowering, being limited by the lateral stops 19 which come to rest on the arms 14 as seen in Fig. 3.

From the foregoing, taken in connection with the accompanying drawings, it will be seen that novel and advantageous provision has been made for carrying out the object of the invention, and while preferred construction has been illustrated, attention is again invited to the possibility of making variations within the scope of the invention as claimed.

I claim:

1. In a bed, an end member, a mattress-carrying frame having an end near said end member, two vertically swingable arms pivoted to said end member on aligned axes extending transversely of the bed, whereby the arms swing in vertical planes adjacent the outer sides of the mattress-carrying frame, and a rod extending between and secured to said arms in spaced parallel relation with said axes, said frame end being provided with means to receive said rod when said arms occupy a substantially vertical position, said frame being provided with notches opening toward said frame end to receive said rod when said arms are substantially horizontal, said frame sides having lateral lugs to lie upon said arms when said arms are substantially horizontal and said rod in said notches.

2. In a bed, an end member, a mattress-carrying frame having an end near said end member, two arms pivoted to said end member on axes aligned transversely of the bed to swing vertically in planes at the outer sides of said frame, the free ends of said arms being provided with rigid inwardly projecting portions, said frame end being provided with a rigid supporting portion to rest upon said inwardly projecting portions at the free ends of said arms when said arms occupy a substantially vertical position, said frame being provided with rigid hooks to underlie said inwardly projecting portions at the free ends of said arms when said arms are swung to a substantially horizontally position, said frame sides having rigid lateral lugs between said supporting portion of said frame and said hooks to lie upon said arms when said arms are substantially horizontal and said inwardly projecting portions at the free ends of said arms are engaged with said hooks, whereby said arms are then held against downward swinging.

ROMAN B. BUKOLT.
